UNITED STATES PATENT OFFICE.

GEORGE W. PEASE, OF PITTSFIELD, MASSACHUSETTS.

GARMENT.

1,273,532.

Specification of Letters Patent. Patented July 23, 1918.

Application filed February 8, 1916. Serial No. 76,886.

To all whom it may concern:

Be it known that I, GEORGE W. PEASE, a citizen of the United States, resident of Pittsfield, county of Berkshire, State of Massachusetts, have invented a certain new and useful Garment, of which the following is a specification.

This invention relates to garments such as overalls, pajamas and the like, and has 10 for its objects,

First: To permit the back drop to be readily lowered or raised when desired.

Second: To have a close and snug fit of the garment at the back and at the same time 15 permit the wearer to stoop or bend.

Third: To exclude dust at the joint between the coat and the top of the back drop.

Fourth: To produce a garment which may be washed without the necessity of ripping 20 out any of its parts.

These and further objects will more fully appear in the following specification and accompanying drawings, considered together or separately.

25 In all union garments having back drops it is necessary to support the center of the back drop from the back of the coat portion to prevent a gap being formed between the top of the back drop and the bottom of the 30 coat when the wearer bends over forward and in order to prevent undue strains on such fastening means an elastic suspender is secured to the coat and its free ends are secured to buttons on the back drop. These 35 suspenders are composed largely of rubber which rapidly disintegrates when subjected to moisture. For this reason when it is desired to wash the garment the suspender is ripped from the coat and must be sewed in 40 place after the garment has dried.

In my improved garment no rubber is employed and the article may be laundered without removing any of its parts.

In the drawings,

45 Figure 1 is a perspective view of a portion of a union garment embodying my invention, showing the back drop raised and secured in place;

Fig. 2 is a similar view showing the back 50 drop lowered;

Fig. 3 is a vertical sectional view taken on the line 3, 3 of Fig 1 but on a larger scale;

Fig. 4 is an elevation of a portion of the inside of the back of the coat showing a 55 portion of the means for supporting the back drop;

Fig. 5 is a top view of a modification;

Fig. 6 is an elevation of the same;

Fig. 7 is a similar view of another modification; and

60 Figs. 8 and 9 are views of a separate jumper or coat and trousers respectively.

In all views like parts are designated by the same reference characters.

In the drawings, 1 designates the coat, 65 jumper or jacket and 2 the trousers or pants. These garments may be made separately or may be permanently connected if desired. When permanently connected they are stitched or otherwise united at the front. 70 The trousers 2 are provided with a back drop 3, formed by slits along the sides from the waist down a sufficient distance so that the drop may be lowered the necessary amount, 75 for example to the extent shown in Fig. 2. This back drop when raised is held in elevated position by a suitable support 4. The corners of the back drop are provided with suitable fastenings 5, for example buttons. These fastenings are adapted to engage with 80 the coat 1 by suitable button holes 6. In addition to these fastenings, fastenings 7 may be employed, such as buttons as illustrated, and these will engage in suitable holes 8 formed in the front part of the 85 trousers 2.

The support 4 is carried by the back of the coat 2 at some distance above the upper edge of the back drop. As shown in Fig. 4, one way of arranging this support is to provide a band 9 which may be stitched or otherwise secured to the inside of the back of the coat 1. This band is preferably made of cloth and may be of the same material as the coat. A second band 9' is secured in 90 place on the band 9. Certain parts of this band 9' are not stitched to the band 9 but are free at the point 10. In the center of this free portion is secured a loop 11. Through this loop is passed a strap or cord 100 12 having eyes at the end adapted to engage with buttons or other fastenings 13 on the back drop. There is a certain amount of give in such a connection. The free part 10 of the band 9' will yield when the wearer 105 stoops or bends over. The points where the free portion of the band 9' are attached to the band 9 will be drawn toward each other thus increasing the distance between the band 9 and the top of the back drop. This 110 yielding motion is transmitted to the full length of the band and width of the coat

thereby securing a yielding connection between the coat and the back drop without the need of using elastic parts.

For the purpose of preventing entrance of dust in the joint between the back drop and coat I provide a dust excluding flap 14. This flap may be made of the same material as the coat. It is secured to the back of the latter preferably at the band 9. It should 10 be preferably as wide as the back drop and should extend below the upper edge of the same, as shown in Fig. 2. This flap need not be secured at its bottom or sides. In addition to preventing the entrance of dust at 15 the joint it also protects the inner garments of the wearer from wear caused by contact with the support 4.

Figs. 5 and 6 show a modification of the support 4 in which the band 9' does not 20 extend the whole or a considerable width of the back of the coat, but is relatively short. The band 9' is directly secured to the coat. In place of the loop 11 a strap 15 is employed. This strap may be made of in- 25 elastic material. Upon the strap is a buckle 16 having a suitable loop whereby it may be attached to a button on the back drop. When this form of support is employed a separate strap and loop is employed for each 30 button 13, depending upon the number of buttons used.

In Fig. 7 is shown another modification in which a two-part clasp 17 is employed. With this clasp the two parts may be 35 separated when it is desired to lower the back drop, the strap or cord 12 remaining in place upon the back drop. The support 4 irrespective of the manner it is made, may be readily removed from the garment when 40 the latter is laundered or cleaned. While I have shown but a single support 4 it is to be understood that more may be employed if desired. As hereinbefore stated the invention may be used in connection with a union 45 garment or one in which the coat and trousers are separated.

Figs. 8 and 9 illustrate a construction in which the coat and trousers are separate. In use the two are buttoned or otherwise 50 connected at the front.

In the form of attachment means shown in Figs. 5, 6 and 7 when it is desired to

launder the garment the buckles may be readily removed from the straps 15 which as it contains no rubber, will not be injured. 55

In accordance with the provisions of the patent statutes I have described the principle of my invention, together with the apparatus which I now consider to represent the best embodiment thereof; but I desire to 60 have it understood that the apparatus shown is merely illustrative and that the invention may be carried out in other ways.

Having now described my invention, what I claim as new and desire to secure by Let- 65 ters Patent, is:

1. A garment having in combination a coat and trousers, a back drop on the trousers, and a support carried by the coat and engaging with the back drop, the said support being connected to the coat at points above the upper edge of the back drop at the sides of the center line of the back of the coat, that portion of the support at the center line of the coat being unattached to 70 the coat so that when a strain is put upon the support it will draw the coat from the sides toward the center. 75

2. A garment comprising a coat and trousers, a back drop on the trousers, a transverse band connected across the back of the coat, said band having a part unattached at the center of the coat, and an inelastic support connecting said unattached part to 80 the back drop. 85

3. A garment support comprising a strip of material secured at each end to a part of the garment at one side of the center of the back of the garment, there being a portion of the strip intermediate the ends and at the center of the back of the garment unsecured to the garment, a strap of inelastic material permanently secured at one end to the unsecured portion of the strip, and means removably carried by the free end of the strap 90 for removably attaching the same to another part of the garment. 95

This specification signed and witnessed this seventh day of February, 1916.

GEORGE W. PEASE.
